US00D830521S

(12) **United States Design Patent** (10) **Patent No.:** **US D830,521 S**
(45) **Date of Patent:** **** Oct. 9, 2018**

(54) **HANDLE**

- (71) Applicant: **Kohler Co.**, Kohler, WI (US)
- (72) Inventors: **Laura K. Kirar**, Miami Beach, FL (US); **William C. McKeone**, Sheboygan, WI (US)
- (73) Assignee: **KOHLER CO.**, Kohler, WI (US)
- (**) Term: **15 Years**
- (21) Appl. No.: **29/645,869**
- (22) Filed: **Apr. 30, 2018**

Related U.S. Application Data

- (62) Division of application No. 29/604,244, filed on May 16, 2017, now Pat. No. Des. 822,179, which is a division of application No. 29/540,144, filed on Sep. 21, 2015, now Pat. No. Des. 787,640.

(57) **CLAIM**

We claim the ornamental design for a handle, as shown and described.

DESCRIPTION

FIG. 1 is a perspective view of an embodiment of the claimed design;

FIG. 2 is a front view thereof;

FIG. 3 is a rear view thereof;

FIG. 4 is a side view thereof;

FIG. 5 is a top view thereof; and,

FIG. 6 is a bottom view thereof.

The ornamental design which is claimed is shown in solid lines in the drawings. The broken lines in the drawings form no part of the claimed design. Broken lines formed by equal length dashes show unclaimed subject matter.

1 Claim, 6 Drawing Sheets
